(57) **CLAIM**

The ornamental design for an X-ray device for unmanned aerial vehicles, as shown and described.

DESCRIPTION

FIG. 1 is a top plan view of an X-ray device for unmanned aerial vehicles showing our new design;

FIG. 2 is a rear elevation view thereof;

FIG. 3 is a front elevation view thereof;

FIG. 4 is a bottom plan view thereof;

FIG. 5 is a first perspective view thereof;

FIG. 6 is a second perspective view thereof;

FIG. 7 is a third perspective thereof;

FIG. 8 is a left elevation view thereof; and,

FIG. 9 is a right elevation view thereof.

The broken line shown in the drawings are for the purpose of illustrating environment and form no part of the claimed design.

1 Claim, 8 Drawing Sheets
